UNITED STATES PATENT OFFICE.

FRANK MACVICAR, OF SYRACUSE, NEW YORK.

VALVE.

1,185,516.

Specification of Letters Patent.

Patented May 30, 1916.

Application filed November 27, 1915. Serial No. 63,7

REISSUED.

To all whom it may concern:

Be it known that I, FRANK MACVICAR, a citizen of the United States, residing at Syracuse, in the county of Onondaga and 5 State of New York, have invented new and useful Improvements in Valves, of which the following is a specification.

This invention relates to internal combustion engines and has particular reference to 10 improved mechanism for controlling the opening and closing movements of the valve therefor.

With motors of this character now in general use, it has been learned that the valve 15 springs fail to cause the tappets to remain in engagement with the cam when the latter travels at a high rate of speed, thereby materially decreasing the efficiency of the motor, and necessitating the cam to operate 20 against both the resistance of the spring and the pressure of the valve, thus subjecting the cam or cams to undue wear.

It is the primary object of my invention 25 to eliminate these objections, by providing a cam controlled valve mechanism, embodying a yieldable means for holding the tappets in continuous engagement with the opening and closing cams respectively, the closing cam possessing a greater throw than 30 the opening cam with a view of tensioning said yieldable means for the purpose mentioned.

Another object of importance resides in 35 the provision of the above mentioned mechanism, wherein said yieldable means serves to cushion the extra throw of the closing cam, thereby eliminating bottoming as the valve engages its seat.

In carrying out my invention I aim to 40 provide a cam controlled valve mechanism, which will materially lessen the wear upon the cams and necessitate the use of less power to operate said valves.

The nature and advantages of the invention 45 will be thoroughly understood when the following description is taken in connection with the accompanying drawings, the invention residing in the construction, combination and arrangement of parts as 50 claimed.

In the drawings forming part of this specification like numerals of reference indicate similar parts throughout the several 55 views and wherein:

Figure 1 is an elevation of the preferred form of the invention showing the normal

position of parts when the valve is closed. Fig. 2 is a similar view showing the active position of the parts when the valve is opened. Fig. 3 is a perspective view of the 60 cam. Fig. 4 is an elevation of a modified form of the invention showing the valve closed. Fig. 5 is a similar view showing the valve opened.

Referring to the drawings in detail, 5 indicates the engine cylinder having the usual seat 6 and the inwardly opening valve 7, the stem 8 of the latter being slidably mounted within the guide 9 and adapted to be operated in the manner to be presently described. As shown in Figs. 1 and 2 I make use of a pair of spaced superimposed rocker arms 10 and 11 respectively, which arms are fulcrumed at a point approximately midway of their length as at 12. The rocker arm 10 is operatively associated in any suitable manner with the upper end of the valve stem 8 while the lowermost rocker 11 has its forward end provided with an opening 13 through which the stem is adapted to slide. The opposite end of each rocker carries a roller 14 and 15 respectively, the latter normally engaging the cam 16 while the roller 15 normally contacts the cam 17, which cams are arranged upon the shaft 18. Encircling the 75 stem 8 is a coil spring 21 disposed between the rocker arms 10 and 11 respectively. The spring has one end seated upon the forward end of the rocker arm 11 while the opposite 80 end of the spring engages a nut 22 adjustably mounted upon the valve stem 8 at its upper end, and by means of which the tension of the spring can be readily and easily regulated. In the position of parts as shown 85 in Fig. 1, the spring is compressed and under 90 tension, for the expressed purpose of maintaining the rollers 14 and 15 in continuous engagement with their respective cams, irrespective of the speed at which these cams may travel. The cam 16 is of usual construction, and when the actuating surface 19 thereof engages the roller 14, the rocker arm 10 is moved upon its fulcrum depressing the 95 valve stem 8 and moving the valve to opened position as clearly illustrated in Fig. 2. In 100 this position of parts the roller 15 is received within the depressed or dished portion 20 of the cam 17, which portion is arranged diametrically opposite the actuating surface 19 of the cam 16 and which arrangement 105 permits of the expansion of the spring 21.

It is of course to be understood that as the actuating surface 19 of the cam 16 is moved out of engagement with the roller 14, the cam 16 is also being rotated to bring its highest portion of the depression 20 into active engagement with the roller 15, at which time the stem 8 is moved in a reverse direction for the purpose of seating the valve 7. It is manifest from the relative 10 dimensions and formations of the respective cams 16 and 17, that the closing cam 17 has a greater throw than that possessed by the opening cam 16, by reason of which fact the spring 21 is not in any way affected 15 by the operation of the cam 17 in the closing of the valve. However subsequent to the seating of the valve 7, the spring 21 serving as a cushioning means to take care of the extra throw of the closing cam 17, is compressed and movement equal to the difference 20 between the throws of the respective cams, during which operation of the spring, the latter is again placed under tension in the position of parts shown in Fig. 1, for the 25 purpose hereinabove stated of holding the rollers 14 and 15 in continuous engagement with their respective cams. This construction and contemplated operation effectively closes the valve without the cam bottoming 30 when the valve strikes its seat, and provides means whereby the cams are operated with considerable less power, and also less wear upon the cam.

In the modified form of the invention disclosed in Figs. 3 to 5, the cams 23 and 24 are constructed and arranged upon the shaft 25 in identically the same manner as the cams 16 and 17 respectively as hereinabove described. However the tappet as shown in 35 this form of the invention preferably consists of a rectangular frame 26 within which the shaft 25 and the cams are arranged to operate. It might here be stated that this embodiment of the invention may be arranged immediately above the valve in the manner illustrated or it can be used by placing the cam shaft in the base of the motor and also where the valves are in horizontal position in the cylinders. The upper and 40 lower members 27 and 28 of the frame are provided with semicircular projections 29 and 30 respectively, the closing cam 24 operating upon the projection 29 around its entire circumference, while the actuating 45 surface 21 of the opening cam 23 operates upon the projection 30. The lower member 28 has depending centrally therefrom an extension 32 slidably fitted within a suitable guide 33 and carries at its free end a relatively large casing 34. The lower end of 50 the casing 34 is closed by means of a nut 35 which is adjustably associated with the casing, and slidably passed through the central opening in the nut is a valve stem 36 55 of the valve 37. The upper end of the valve

stem is normally spaced a slight distance from the adjacent end of the casing 34, which distance is equal to the difference of throw between the opening and closing cams respectively, the purpose of which will be 70 presently described. Arranged within the casing 35 and encircling the stem 36 is a coil spring 39 having one end seated upon the nut 35 and its opposite end engaging a nut 38 adjustably mounted upon the upper end 75 of the stem 36 for the purpose of regulating the tension of the spring.

Now as the shaft 25 is rotated and the actuating surface 31 of the cam 23 brought into engagement with the projection 30, the 80 tappet including the frame 26, extension 32, and casing 34 is moved against the valve stem 36, thereby moving the valve 37 away from its seat, as shown in Fig. 5. In the normal or closed position of the valve as 85 shown in Fig. 4 the spring 39 is compressed and under tension, but when the valve is moved to opened position as shown in Fig. 5 this spring is permitted to expand, thereby moving the valve stem 36 into engagement with the upper end of the casing 34. As the shaft 35 is rotated to move the actuating surface 31 of the cam 23 out of engagement with the projection 30, the cam 24 is simultaneously rotated to bring the 90 highest portion of the depression 40 thereof into engagement with the projection 29 thereby moving the tappet in its entirety in a direction opposite that in which it was moved by the cam 23 for the purpose of 95 seating the valve 37. The relative dimensions and formations of the respective cams, attributes to the closing cam 24 a slightly greater throw than that possessed by the opening cam 23, and subsequent to the closing 100 of the valve 37 by means of the cam 24, the spring 39 acts as a cushion for the extra throw of the closing cam, to take care of the extra throw of the latter, and is thereby placed under tension whereupon the various 105 parts assume their normal position as clearly illustrated in Fig. 4. It will be clear from the foregoing description, when considered in connection with the accompanying drawings that I have devised a means whereby 110 the tappet or tappets are caused to continuously engage the cams for operating the latter, which not only eliminates considerable wear upon these parts, but renders the valve to be more easily and properly timed when 115 the cam shaft travels at a high rate of speed. While I have shown and described several embodiments of the invention I desire to have it understood that I do not limit myself to this precise construction and arrangement of parts, and that various changes 120 may be resorted to when desired as fall within the scope of the appended claims.

What is claimed is:—

1. The combination with a cylinder of an 120

internal combustion engine, and a valve therefor, of valve operating mechanism including opening and closing cams respectively, a valve actuating device adapted to engage the opening and closing cams respectively, and a yieldable means for holding the device in continuous engagement with said cams.

2. The combination with a cylinder of an internal combustion engine and valve therefor, of valve operating mechanism including opening and closing cams respectively, a valve actuating device adapted to engage the opening and closing cams respectively, a yieldable means for holding said device in continuous engagement with said cams, and means for regulating the tension of said yieldable means.

3. The combination with a cylinder of an internal combustion engine, and a valve therefor, of a valve operating mechanism including opening and closing cams respectively, a valve actuating device adapted to engage the opening and closing cams respectively, yieldable means normally under tension for holding said device in continuous engagement with said cams, one of said cams decreasing the tension of said means, and the other of said cams placing said means under tension.

4. The combination with a cylinder of an internal combustion engine, and a valve therefor, of a valve operating mechanism including opening and closing cams respectively, a valve actuating device adapted to engage said cams, an extensile spring encircling the valve stem and operating to hold the valve actuating device in continuous en-

gagement with the respective cams, and means for regulating the tension of said spring.

5. The combination with a cylinder of an internal combustion engine, and a valve therefor, of a cam controlled valve mechanism including a tappet operatively associated with the valve and adapted to engage the opening and closing cams respectively, a yieldable means operating to hold said tappet in continuous engagement with said cams, and said closing cam having a greater throw than the opening cam for compressing and placing said yieldable means under tension as described.

6. In combination with a cylinder of an internal combustion engine, and a valve therefor, of a tappet including a pair of spaced parallel rocking arms, one of said arms being terminally associated with the stem of the valve, said stem being slidably fitted in the adjacent end of the other of said arms, a cam for operating said arms to open the valve, a second cam operating to close said valve, a yieldable means interposed between said arms operating to hold the latter in continuous engagement with their respective cams, and one of said cams having a greater throw than the other for compressing and placing said yieldable means under tension.

In testimony whereof I affix my signature in presence of two witnesses.

FRANK MACVICAR.
